UNITED STATES PATENT OFFICE

130,991

DESIGN FOR A CANDLE HOLDER

Clarence F. Gray, Syracuse, N. Y.

Application August 9, 1941, Serial No. 102,778

Term of patent 14 years

To all whom it may concern:

Be it known that I, Clarence F. Gray, a citizen of the United States of America, residing at Syracuse, county of Onondaga, and State of New York, have invented a new, original, and ornamental Design for a Candle Holder, of which the following is a specification, reference being had to the accompanying drawing, forming a part thereof wherein:

I claim:

The ornamental design for a candle holder, as shown.

CLARENCE F. GRAY.
